UNITED STATES PATENT OFFICE

MAGNUS E. WIDELL, OF CINCINNATI, OHIO, ASSIGNOR TO AMERICAN CAN COMPANY, OF NEW YORK, N. Y., A CORPORATION OF NEW JERSEY

MACHINE FOR FORMING METAL BANDS

Application filed January 23, 1929. Serial No. 384,536.

This invention relates to machines for forming metal bands, particularly of that type which are adapted for insertion into the body of a can to form an interior collar band 5 upon which a severed upper portion of the body may be positioned as a temporary closure after being separated by the removal of a tearing strip or in other manner.

A principal object of the present invention is the provision of a machine which automatically operates directly upon metallic sheets, dividing them into strips of proper outline and size, which forms the strips into annular shape and which overlaps and welds the ends thereof, thereby providing annular metal bands, all of the various operating parts being so related and actuated as to render possible a high rate of production.

Another and very important object of the invention is the provision, in a machine of this character, of notching devices for producing a notched end on a band strip, the strip being subsequently formed into annular shape with its ends lapped and welded together, the notched end being on the inside of the lap and forming a relatively smooth joint of great strength.

Still another important object of the invention is the provision, in a machine of this character, of embossing dies which imprint embossed portions in the ends of a band strip, the embossed portions on one end of the strip being angularly disposed relative to those on the other end, whereby said embossed portions engage one another in a series of contact points when the ends of the strip are overlapped, these contact points determining the position of the welding bond when the strip ends are welded together.

Another object of the invention is the provision, in a machine of this character, of feeding rollers and locating devices for positioning and holding a sheet for the notching and the strip cutting operations.

Numerous other objects and advantages of the invention will be apparent as it is better understood from the following description, which, taken in connection with the accompanying drawings, discloses a preferred embodiment thereof.

Referring to the drawings:

Figure 1 is a front elevation of the machine of the present invention, parts being broken away;

Fig. 2 is a side elevation, parts being broken away;

Fig. 2a is a sectional detail taken substantially along the line 2a-2a in Fig. 3;

Fig. 3 is a rear elevation;

Fig. 4 is an enlarged sectional view taken substantially along line 4-4 in Fig. 1;

Fig. 5 is an enlarged partial elevation, partial sectional view taken substantially along line 5-5 of Fig. 1;

Fig. 6 is an enlarged fragmentary end detail partially in section of the notching mechanism, showing a sheet in its initial notching position;

Fig. 7 is a view similar to Fig. 6 illustrating a sheet in a different position relative to the notching mechanism;

Fig. 8 is an enlarged longitudinal section taken substantially along line 8-8 of Fig. 3;

Fig. 9 is an enlarged transverse sectional view taken substantially along line 9-9 of Fig. 8;

Fig. 10 is an enlarged end elevation of the parts shown in Fig. 8, parts being broken away;

Fig. 11 is an enlarged fragmentary plan view of the separated ends of a strip after the ends have been embossed;

Fig. 12 is an enlarged side elevation of the two ends of a strip after being brought into overlapping position;

Fig. 13 is a perspective view of the completed welded metal collar band, and

Fig. 14 is a fragmentary detail of the gearing for driving the feeding and forming rollers of the machine, parts being shown in section.

The present invention relates to a type of machine such as is disclosed in my pending application, Serial No. 636,338 filed May 3, 1923. The present machine is designed to form a metal band and weld the ends together, whereas in the aforementioned application, a metal band is formed with its ends riveted together.

The machine of the present invention in

a series of feeding and forming operations produces a metal band 21 (as shown in Fig. 13), the band issuing from the discharge end of the machine and being formed from a sheet 22 of tin plate or other suitable sheet material fed into the entrance end of the machine. During the passage of sheets 22 and parts thereof through the machine, notches 23 (Figs. 6, 7 and 11) are first cut in one edge of each sheet 22 after which a strip 24 with one notched end is severed from the sheet. A series of rollers (Fig. 1), then form the strip 24 into annular shape and position it upon a forming mandrel, after which die mechanism (Figs. 8 and 9), operating in conjunction with holding or clamping devices, embosses the ends of the strip and prepares them for welding. Assembling mechanism (Fig. 10) then overlaps the ends of the strip and the embossed portions thereon are brought into contact with each other, after which electrodes engage and clamp the overlapped ends of the strip. The held strip ends are then welded together by an electric welding current properly controlled by an improved switch device.

The principal parts of the apparatus are supported by a frame 25 (Figs. 1 and 3) on which is mounted a bed or table 26. Operating power for the machine is supplied from a suitable source through the medium of a pulley 27 carried by a drive shaft 28, journaled in bearings 29 formed in frame 25. A pinion 31 secured to shaft 28 meshes with a gear 32 carried on a main cam shaft 33 journaled in bearings 34 formed in frame 25.

Sheets 22 are introduced into the machine in suitable manner, each sheet being positioned vertically adjacent one face of a retaining plate 35 (Figs. 1 and 3) formed integrally with brackets 36 carried by and projecting upwardly from the table 26. The sheet is moved downwardly along the plate 35 in a step by step movement, more fully described hereinafter and during such movement the side edges of the sheet pass along slots or grooves formed in end members 37 and 38 positioned adjacent plate 35. End member 37 is secured by bolts 40 to the plate 35, and end member 38 is adjustable transversely of the plate 35 to vary the distance between the grooves in the end members for accommodation of sheets of different width.

Movement of member 38 from one position to another is accomplished by means of an adjusting screw 39 having a bearing in a bracket 41 carried by one of the brackets 36, screw 39 having threaded engagement with a T-block 42 (Fig. 4), positioned in a guideway 43 formed transversely of plate 35. The block 42 carries a threaded stud 30 which projects through member 38, the end of the stud being threadedly engaged by a lock nut clamping against the face of said

member 38. When the described parts are in locked position the head of block 42 is clamped against walls of the guideway 43 and end member 38 is clamped against the face of plate 35, this being a common form of adjusting and clamping construction. The screw 39 is operated by a thumb nut head. It will be manifest that the construction just described permits the positioning of the adjustable member 38 at any point within the limits of the screw 39.

Rods 44 extend upwardly from the upper side of plate 35 and form extensions of the latter to assist in retaining the sheets in vertical position. A stop plate 45 (Fig. 1) is provided adjacent member 37 and facilitates the positioning of the sheets within the grooves of the end members 37 and 38.

When a sheet is inserted into the machine (Fig. 4), the lower edge thereof rests upon movable fingers 56, a said finger being provided near each side of the plate 35 and each finger extending through an aperture 57 cut through the retaining plate 35. This holds the sheet in position for the first notching operation, to be described later. Each finger 56 is carried in an arm 58 mounted upon a rock shaft 59 journaled in the brackets 36. Set screws 61 extending through arms 58 engage the back of plate 35 and limit the movement in one direction of both arms 58 and rock shaft 59. A rod 62 is mounted in one arm 58 between its finger 56 and the shaft 59 and carries a weight 63 slidably secured thereto, the weight tending to rock the shaft 59 to project the fingers 56 through their respective apertures 57. With the sheet resting upon these fingers 56 in its first notching position (Fig. 6), one edge thereof is engaged by a pair of notching die units cutting V notches 23 in the sheet, a half notch at the corner and a full notch at an interval therefrom and just above the half notch. The center of the upper or full notch is located along a line substantially parallel to the bottom edge of the sheet, this line being a line of severance when the first strip is cut from the sheet in a subsequent operation. The notching die mechanism and the cutting mechanism will be hereinafter fully described.

After notching, fingers 56 are withdrawn from beneath the sheet which is thereon moved downwardly into the cutting mechanism. The mechanism (Fig. 4), for withdrawing fingers 56 comprises an arm 69 pivoted at 71 to a bracket 72 secured to the frame 25. This arm is reciprocated by connection with a reciprocating part of the cutting mechanism.

Arm 69 at its upper end carries a dog 75 loosely mounted on a pivot pin 76. A stop pin 77 secured to the arm 69 limits the movement of dog 75 in one direction, and an outwardly extending pin 78 carried by the dog

75 constitutes a weight for normally holding the lower part of the dog against the stop pin. As arm 69 is moved toward the left (Fig. 4), an inclined face 79 formed in the upper part of dog 75 strikes against an incline 81 formed in one face of the weight 63. These inclined faces sliding on each other force weight 63 upwardly, dog 75 being held in non-rotating position by engagement with the stop pin 77. This lifting of weight 63 causes a corresponding movement of arms 58 accompanied by a rocking of shaft 59 and fingers 56 are thereby withdrawn from the positioned sheet 22. The actions of the lifting of weight 63 and the withdrawing of fingers 56 from their forward position are only momentary but during such a time sheet 22 is lowered into its second position. When weight 63 is released by the passing of dog 75 from beneath, as arm 69 continues its movement toward the left, fingers 56 tend to again move through their slots 57 but are prevented by the sheet 22 then extending across the slots.

It should be evident, therefore, that the fingers 56 only move through their respective slots to support a sheet at its initial notch forming operation and prior to the initial shearing operation. At other times while the sheet is passing through the machine, the forward ends of the fingers 56 rest against the rear surface of the sheet and even though the weight 63 is lifted several times during this passage of the sheet, no effect takes place upon the fingers 56. However, sheets 22 are fed into the machine in processional order and after one sheet has been moved downwardly and passed the said fingers 56 they will move forward under the action of weight 63 and will thus rest in the path of the succeeding sheet and support the same as it moves into its initial notching position.

Upon each return movement of arm 69 (being toward the right in Fig. 4), dog 75 striking against weight 63 rotates about its pivot pin 76 against the action of weight 78 and permits clearance of the arm 69 without lifting the weight 63.

Sheet 22 is moved downwardly along the slots of end members 37 and 38, (Figs. 1 and 4) by feed rollers 47 which frictionally engage one face of the sheet, the opposite face of the sheet being in contact with and moving along the plate 35. Rollers 47 rotate with and are mounted upon a shaft 51 journalled in bearings formed on the end members 37 and 38. Shaft 51 carries a sheave 53 over which operates a rope belt 52 passing over a sheave 54 carried by drive shaft 28. By such a connection rollers 47 are constantly rotated but they effect only an interrupted feeding of sheet 22 which is held from movement, during certain rest periods, the rollers moving idly against the sheet at such times.

Clamping devices assist in holding sheet

22 during its periods of rest, these devices comprising clamping arms 46 adjustably held by set screws on a rock shaft 48. Shaft 48 is rocked within bearings carried by the end members 37 and 38, and this rocking action moves the arms 46 into clamping engagement with the sheet. An arm 49 (Fig. 1) secured to shaft 48 is pivotally connected to an arm 50 extending from one side wall of a sliding bed member 67 moving over table 26 and sliding within guideways 55 formed in the table.

Bed 67, (Figs. 1 and 4) is moved back and forth by a cam controlled mechanism comprising links 201 pivoted to the rear end of the bed and connecting with arms 202 extending upwardly from a sleeve 203 oscillating about a shaft 204 mounted in brackets 205 carried by the table 26. Sleeve 203 also carries an arm 206 pivotally attached to one end of a connecting rod 207, the other end of the rod carrying a cam yoke 208 (Fig. 3) sliding over a shaft 33 and being moved back and forth by a cam 209 cooperating with a cam roller 208' (see also Fig. 2a) carried by the yoke 208, the cam 209 being also mounted upon shaft 33.

It is this movement of bed 67 that is communicated to the arm 69 previously described. A link 73 (Fig. 4), forms the proper connection by being pivotally attached to a pivot yoke 74 carried by bed 67 and being also pivotally attached at its opposite end to arm 69.

The notching die units, (Figs. 5, 6 and 7) comprise a pair of metal punches 64 adjustably mounted in a cross head 66 carried by the bed 67. Upon each forward reciprocation of bed 67 the punches pass through one edge of the sheet and enter within cooperating die members 65 carried in the bottom part of the plate 35. This co-action of members 67 and 65 forms the notches 23 in the sheet, the metal clips removed from the sheet passing into channels 60 formed in plate 35. The notching punches are slidably supported in an extension 80 of end member 37 (see also Fig. 1).

The first notching operation performed upon a sheet 22 takes place while the bottom edge rests upon the fingers 56 as shown in Fig. 6. Fingers 56 are then withdrawn and the sheet is moved downwardly, by the mechanisms just described, coming to rest with its bottom edge resting in a groove 82 (Fig. 4), cut in the upper surface of a slide 83, this position of the sheet being shown in Fig. 7. The sheet so positioned is ready for the second notching operation and the first strip severing operation.

Upon the next forward movement of bed 67 the notching die units again cooperate to notch the edge of the sheet and simultaneously a shear blade 68 mounted upon the forward end of bed 67 cooperates with a fixed shear

blade 70 secured to bracket 36, (Fig. 4), and severs the first strip 24 from the sheet. The blade 68 pushes against the top of the strip as it is detached from the sheet and the same 5 rocks about its lower edge, which is loosely confined within the groove 82 of the slide 83, and falls into a horizontal position upon the slide. In this position it is adjacent a stop shoulder 86 formed in the slide. Following 10 this first cutting operation and following each subsequent cutting operation the remaining part of sheet 22 is lowered, each time by the feeding devices previously described, until its bottom edge rests within groove 82 15 and upon slide 83.

It will be evident by reference to Figs. 6 and 7, that the distance of travel of sheet 22 from its first notching position to its second notching position is greater than its distance 20 of travel between subsequent notching positions. After the second notching operation is performed, and just prior to the first cutting operation, there are four notches 23 in the edge of the sheet. The severing of a strip 24 25 from the sheet, removes only a strip whose width is equal to the distance between the two notching die units. Just prior to the third and subsequent notching operations, and following the placing of the remaining 30 part of the sheet in lowered position, the top notch is in top register with the lower notching die parts 64 and 65. The said punch 64 thereupon passes through the notch without performing any operation upon the sheet. 35 For the third and all subsequent notching operations therefore, on any particular sheet only the upper notch is cut until the sheet has been passed entirely through the notching mechanism. 40 Strip 24 resting upon the slide 83 is moved longitudinally of its length first by a shifting of the slide 83 and then by feeding and forming rollers. These rollers remove the strip from the slide and position it about a forming 45 mandrel. The slide moving mechanism will now be described.

Slide 83, (Fig. 4) rests upon and moves back and forth over the upper surface of a bracket 85 adjustably bolted in fixed position 50 upon a wall of table 26. A tongue and groove connection 84 between the slide 83 and the bracket 85 permits relative longitudinal movement and at the same time retains the slide in its proper path of travel.

Slide 83 (Fig. 3), is moved back and forth by connection with shaft 33, this mechanism comprising an extension 211 formed in one end of slide 83 and pivotally connected to an adjustable link 212 which in turn is pivotally 55 connected to an arm 213 secured to a rock shaft 214 journalled in frame 25. An arm 215 is also secured to rock shaft 214 and carries a cam following roller operating within the cam groove of a barrel cam 220 carried by 60 shaft 33. The cam 220 operating through

the described mechanism holds slide 83 stationary during the feeding of the bottom edge 70 of sheet 22 into the groove 82 and during the following shearing operation just described, and moves the slide 83 over the surface of bracket 85 during the feeding of the forward end of the strip into the feeding rollers.

There are two pairs of feeding and forming rollers, the first pair comprising cooperating rollers 87 mounted on parallel shafts 216 rotating within a bracket 217 carried on table 26, see Figs. 1 and 14. The lower shaft 216 carries a spur gear 218 which meshes with a gear 91 secured to a horizontal shaft 219 journalled in table 26. Shaft 219 also carries a sprocket 221 over which operates a drive chain 92 passing over a sprocket 93 mounted upon a horizontal shaft 94 journalled in bearings 96 formed in frame 25, see also Fig. 2. Sprocket 93 is connected to shaft 94 through a friction slip clutch 95 which causes normal 85 turning of the sprocket 93 during rotation of shaft 94. In the event of any abnormal condition arising at the feeding rollers 87 the slip clutch 95 will permit stopping of the sprocket 93 without affecting the rotation of the shaft 94. Shaft 94 carries a mitre gear 97 meshing with a corresponding gear 98 secured to the horizontal shaft 28.

Rollers 87, (Fig. 14) engage the forward edge of a strip 24 as it is moved by the slide 83 and advance the strip to a second pair of rollers 88. These latter rollers constitute forming rollers and are mounted upon parallel shafts 222, the upper shaft rotating within a horizontal forming mandrel 89, the lower shaft being journalled within a block 223 carried by table 26. Shafts 222 carry cooperating pinions 224 the lower pinion engaging the teeth of gear 91. Rotation of the said gear 91, therefore, causes a corresponding rotation of the forming rollers 88. Both sets of rollers 87 and 88 are the same diameter and rotate at the same speed the former set smoothing or ironing out any burrs or irregularities that might exist in the strip 24. Either pair of rollers 87 or 88 may also slightly bend or curl the edges of the strip as at 19 (Fig. 13) where this is desirable.

As the strip 24, (Figs 1 and 14) moves through rollers 88, it is directed against a deflecting plate 225 secured to the block 223. The forward edge of said plate is rounded and serves to direct the strip about the end of the mandrel 89 and at the same time shapes it into annular form. During this movement around the mandrel the strip passes along the inner faces of retaining blocks 229 and 231, each pivoted to the bed 26, and being held in strip retaining position by springs 232, see Fig. 1.

Mandrel 89 is supported on bed 26 throughout a major part of its length and the strips 24, after being brought to annular form thereupon are advanced with an intermittent mo-

tion along said mandrel by means of the usual sliding bar type of feeding devices. These devices comprise four feed bars 101, (Figs. 1, 2 and 9) positioned in longitudinal grooves formed in the mandrel 89. The outside faces of the bars are flush with the outside surface of the mandrel. The bars move back and forth within their grooves, and inside of the annular strips or bands 24 resting on the mandrel. Each bar 101 carries the usual spaced spring-pressed dogs 103 which engage the formed bands and move them forward with the forward movement of the bars.

15 The bars 101 extend backwardly beyond the end of the mandrel 89 and are secured to a disc 102, connected by a link 105 with a lever arm 104 formed integrally with a sleeve 90 mounted on a shaft 106 held in brackets 107 depending from the under side of table 26. Sleeve 90 is provided with a depending arm 100 connected by a rod 108 with a cam yoke 109, (Fig. 3) provided with a cam following roller which operates within a groove formed 25 in a cam 111 secured to shaft 33.

During the reciprocation of feed bars 101 the dogs 103 engage and advance the bands on the forward stroke and pass beneath the same, on the backward stroke, the yielding 30 of their springs permitting this latter action. The bands 24, (Fig. 9) are held in each advanced position by retaining dogs 226 spring held within channel bars 227, positioned about the mandrel. These dogs are 35 depressed by contact with the advancing bands and engage behind them upon the backward stroke of the feed bars, this action holding the bands until again engaged by the spring dogs 103 on the feed bars 101.

40 The band passes along the mandrel through a number of idle stations and finally comes to rest at the embossing station. It is engaged during its rest period by a clamping bar 112 (Fig. 8) which is positioned directly above the mandrel. Bar 112 is yielding 45ly held against the mandrel at its rear end by a spring 116 positioned about a bolt 117 secured to a portion of the bracket 36, (Fig. 2). The other end of the bar, (Figs. 2, 8 and 9) is attached to a rod 118 extending through a bearing formed in a yoke 119 mounted upon frame 25. The upper end of the rod 118 is yieldingly connected with a cross arm 121 adjustably secured to the upper end of a vertical rod 122 passing through a bearing in yoke 119 and connecting at its lower end to a cross head 123.

45 Cross head 123 is attached to a connecting rod 152 (Figs. 2 and 3) which is adjustably secured to a lever 153 pivoted about a shaft 160. Lever 153 carries a cam following roller 154 engaging a cam groove formed in a face cam 155, carried by shaft 33. When lever 153 is moved downwardly, rod 122 is correspondingly lowered and the cross arm 121

compressing the spring at the top of rod 118, forces the latter downwardly. This clamps bar 112 against band 24 and holds it on the top of the mandrel 89.

With the annular band, at the embossing station, so clamped, it is next engaged by side wings 113, (Fig. 9) which bring the ends of the band into operative relationship with embossing die units. Each side wing 113, is supported by a pair of parallel arms comprising a straight arm 125 and a bell crank 124 pivoted respectively upon shafts 120 and 126 journalled in bearings 127 formed in yoke 119. The lower end of each bell crank 124 (Figs. 2 and 3), is pivotally connected to a rod 128 secured to a plate 131, which carries a rod 195 yieldingly connected through a spring 157, with a cross head 196 formed integrally with an extension 156 secured at its bottom end to cross-head 123. Rods 128 are thus raised and lowered and side wings 113 are moved into and out of band engaging position, the engagement being of a yielding nature by reason of the spring connection.

50 The embossing die units (Figs. 8 and 9), comprise a female die 132 and a male die 133 inserted within the mandrel 89. These die parts cooperate respectively with a male die 134 and a female die 135 inserted in the upper end of a slide bar 136 operating within grooves formed in a block 139 secured to frame 25. Block 139 is slotted at 140 to clear cross head 196 (see Fig. 2). Bar 136 is raised and lowered by pivotal connection with an adjustable link 137 which is pivoted at its lower end to a lever 138 in turn pivoted about the shaft 160. Lever 138 carries a cam following roller 141 resting at all times upon a cam 142 secured to shaft 33. A spring 143 extending between the outer end of lever 138 and a bracket fixed to frame 25 holds this roller 141 against its cam 142. Rotation of cam 142 raises and lowers lever 138 and the die members 134 and 135 carried by the bar 136.

55 As bar 136 reaches its uppermost position, dies 134 and 135 pressing against the metal of the ends of the band resting upon mandrel 89, force the metal against the corresponding dies 132 and 133 and thus emboss the ends of the band 24. It will be evident that the displaced metal in one end extends on the inside of the annular band while the displaced metal of the other end extends outwardly, this providing a preferred type 60 of embossed end for the subsequent welding operation. As disclosed in the drawings the die parts 132 and 134 form the embossed portions on the notch end of the band while the dies 133 and 135 form the parallel ridges 65 at the square end of the strip.

65 Following the embossing operation the annular band 24 is released by lowering of bar 136, by outward movement of the wings 113 and by a lifting of clamping bar 112. Bar 130

112 is raised by a mechanism disclosed in Figs. 2, 3 and 8, which comprises a link 197 pivoted to the forward end of the bar 112 and connected at its upper end to an arm 198 secured to a rock shaft 199 journaled in bearings formed in yoke 119. Shaft 199 also carries an arm 190 connected, by a link 200, with the upper end of a lever 239 pivoted in a bracket 240 carried by frame 25. Lever 239 carries a cam following roller 241 engaged during the unclamping of bar 112, by a cam segment 242 attached to the outer periphery of cam 209. Band 24 thus unclamped and resting at the embossing station, is thereupon moved by the feeding mechanism to the welding station.

15 The welding station is located in an auxiliary mandrel 158, (Figs. 8 and 10) bolted to the forward end of the forming mandrel 89. Mandrel 158 is of smaller diameter than the forming mandrel and is of the expanding and contracting type commonly used in can body forming machines. It comprises a fixed central portion 161 and movable side sections 159 interengaged by the usual tongue and groove construction.

20 25 Sections 159 are pressed outwardly into expanded position, to form a complete cylindrical horn by means of a wedge rod 162 moving axially within the mandrel and operating upon cam parts connected with the sections 159 in the usual manner. The mechanism for moving rod 162 comprises a lever 163 (Figs. 2 and 8), pivotally connected therewith, and rocking about a shaft 170 carried by frame 25. The lower end of lever 163 is pivotally connected by an adjustable link 164, to a cam yoke 165 sliding over shaft 33, (Fig. 3), the yoke carrying a cam following roller operating within a cam groove formed in a cam 166 secured to shaft 33.

30 35 Auxiliary mandrel 158 (Figs. 2 and 8) is fully expanded as the band 24 is positioned at the welding station and the latter is clamped upon the mandrel by a clamp bar 114 pivotally secured at its rear end to the bar 112. The forward end of the clamp bar 114 is fixed to an upwardly extending rod 144 which passes through a bearing formed in yoke 119, (Fig. 3). The upper end of rod 144 is yieldingly attached to a cross arm 145 adjustably positioned about a rod 146 extending through a bearing in yoke 119 and connecting at its lower end to cross head 123. When cross head 123 is moved downwardly 40 45 50 55 by the cam mechanism previously described the forward end of bar 114 is clamped under the spring pressure of rod 144 while its rear end, being connected with bar 112 is also clamped under spring pressure through rod 118.

60 With band 24 clamped at the welding station a pair of side wings 115 (Fig. 10) engages the band and overlaps its lower ends, clamping the same in welding position. 65 Each of the side wings 115 is supported by a

pair of parallel arms comprising a straight arm 148 and a bell crank 147 pivoted respectively upon the shafts 120 and 126. The lower arm of each bell crank 147 is pivotally connected to a rod 151 extending downwardly into threaded connection with the plate 131. As plate 131 is lowered the bell cranks 147 are rocked and the side wings 115 are moved into the band clamping position.

70 75 80 85 90 The embossed portions on one of the overlapped ends of a clamped band 24 at the welding station engage the corresponding embossed portions on the other end in a series of contact points. These band ends at that time (Figs. 8 and 10) are directly beneath an upper welding electrode 167 adjustably secured within the bottom part of the auxiliary mandrel 158 by means of a bolt 169, threaded into the forward end of a copper Z bar 171 passing through openings formed in mandrel 89 the bar being clamped to a part of the mandrel by U bolts 129. This bar 171 forms a path for the welding current which is conveyed thereto by a conductor lead 172 hereinafter more fully described. An adjusting bolt 168 threaded into electrode 167 with its head resting against a part of the fixed member 161 permits easy and accurate vertical adjustment of the electrode.

95 100 105 110 115 A lower welding electrode 173 is positioned directly beneath the overlapped ends of the band 24 and is held in a block 176 insulated from but attached by bolts 175 to a sliding bar 174 operating in grooves formed in the block 139. Bar 174 is pivotally connected, through an adjustable link 149 with the outer end of the lever 138 (Fig. 2). It will be evident that bar 174 moves upwardly to position the lower electrode 173 into contact with the overlapped ends of band 24 at the welding station at the same time that bar 136 moves the embossing dies into contact with the ends of another band 24 positioned at the embossing station. A copper lead 177 is bolted to the block 176 and forms a part of the path of travel for the electrical welding current.

120 125 130 135 140 As the lower electrode 173 engages the overlapped ends of band 24 and forces the same against the upper electrode 167 a welding current flows through the electrodes and the contacting points of the embossed portions of the overlapped ends of a band are raised in temperature sufficient to provide a welded bond at those points. As illustrated in Fig. 13, four welded spots are thus created there being two embossed portions on each end of the band, these contacting each other at four points. The number and position of the welded spots is determined by the number, shape or position of the embossed portions of the band ends, the band illustrated showing one preferred welded bond.

130 Provision is made in the welding circuit for timing the electrical impulse used in the weld-

ing operation. This comprises a switch mechanism (Fig. 2), which controls the timing of the welding operation, the associated clamping mechanism being synchronized to permit the parts to cool before the welded band is removed from the mandrel. The switch mechanism also reduces arcing of the current during operation of the switch. The copper leads 172 and 177 connecting with the electrodes 167 and 173 as just described, are in the secondary circuit of any suitable type of electric welding apparatus, the switch mechanism referred to being connected in a primary welding circuit.

Part of the leads for the primary circuit adjacent the switch mechanism (Fig. 2), are indicated by the numerals 179 and 181 leading to a pair of spaced contact blocks 182 secured within but insulated from a housing 183 attached to a bracket 178 secured to frame 25, (see also Fig. 3). The switch for the primary circuit comprises a laminated spring contact bar 184 supported by and moving vertically with a cross head 185, having sliding movement within the housing 183. Cross head 185 carries auxiliary spring pressed contact pins 186 extending slightly beyond the ends of the contact bar 184 and when the cross head 185 is lowered they come into contact with the blocks 182 prior to contact of the bar 184 therewith. In like manner, as cross head 185 is raised, contact pins 186 hold their contacts with blocks 182 after the connection has been broken between the bar 184 and the blocks 182. This arrangement reduces arcing between bar 184 and blocks 182.

Cross head 185 (Fig. 2), is supported from above by a pair of vertical bolts 187 threaded therein and extending through an insulated auxiliary plate 191 secured to and held in a horizontal position by housing 183. The upper ends of bolts 187 pass through and are held in a head member 188 and are surrounded by coil springs 189 interposed between the head member and the auxiliary plate 191. Springs 189, resting on the fixed plate 191 and forcing the head member 188 upwardly, thus tend to hold contact bar 184 in raised position, this being the open position of the switch mechanism. Head member 188 is formed with an upwardly extending stem 192 which projects through the top wall of the housing 183, and which carries a cam roller 193 positioned beneath a cam 194 secured to and rotating with the shaft 33. Stem 192 is properly insulated from roller 193 and housing 183 by means of a bakelite or other suitable section 233. The cam 194 is formed in part by a movable plate 234 mounted on shaft 33 and adjustable relative to the fixed part of the cam. This permits a changing of the cam shape and gives an exact adjustment for the timing of the switch, which is closed when cam 194 depresses stem

192 and cross head 185 and parts carried thereby, this movement being against the action of springs 189.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for forming metal bands, the combination of means for notching one edge only of a sheet, devices for cutting strips of desired size from said sheet, a forming mandrel, mechanism for arranging the severed strips upon said mandrel with their ends overlapped, and means for securing the lapped strip ends together with said notched edge arranged on the inside of the lap to form annular metal bands.

2. In a machine for forming metal bands, the combination of means for notching one edge of a sheet, devices for cutting strips of desired size from said sheet, a forming mandrel, mechanism for arranging the severed strips upon said mandrel with their ends overlapped, and means for welding the lapped strip ends together to form annular metal bands.

3. In a machine for forming metal bands, the combination of means for notching one edge only of a sheet, devices for cutting strips of desired size from said sheet along spaced lines of severance passing through said notches, a forming mandrel, mechanism for arranging the severed strips upon said mandrel with their ends overlapped with said notched edge arranged on the inside of the lap, and means for securing the lapped strip ends together to form annular metal bands.

4. In a machine for forming metal bands, the combination of devices for cutting strips of desired size from a sheet, a forming mandrel, mechanism for arranging the severed strips upon said mandrel, means for embossing the ends of the strip, devices for overlapping the embossed ends of the strips, and means for securing the lapped strip ends together to form annular metal bands.

5. In a machine for forming metal bands, the combination of devices for cutting strips of desired size from a sheet, a forming mandrel, mechanism for arranging the severed strips upon said mandrel, means for embossing the ends of the strips, and means for welding the embossed ends together to form annular metal bands.

6. In a machine for forming metal bands, the combination of devices for cutting strips of desired size from a sheet, a forming mandrel, mechanism for arranging the severed

- strips upon said mandrel, means for embossing the ends of the strip, devices for overlapping the ends of the strips and bringing the embossed portions of one end of each strip into engagement with the embossed portions of the other end, and means for welding the engaged, embossed ends together to form annular metal bands.
7. A machine for forming metal bands, comprising in combination a forming mandrel, mechanism for arranging strips upon said mandrel, means for embossing the ends of the strips while in position upon said mandrel, devices for overlapping the embossed ends of the strip, and welding means for securing the lapped, embossed ends together to form annular metal bands.
8. A machine for forming metal bands, comprising in combination a forming mandrel, mechanism for arranging strips upon said mandrel, means for embossing the ends of the strips while in position upon said mandrel, devices for overlapping the embossed ends of the strip, means for welding the embossed ends together, and instrumentalities for automatically controlling the flow of welding current through said welding means.
9. A machine for forming metal bands, comprising in combination a forming mandrel, mechanism for arranging strips upon said mandrel, means for embossing the ends of the strips, said means comprising fixed embossing dies positioned within said mandrel and movable exterior embossing dies, said fixed and exterior dies operating upon the strips while in position upon said mandrel, devices for overlapping the embossed ends of the strip, and welding means for securing the lapped, embossed ends together to form annular metal bands.
10. In a machine for forming metal bands, the combination of means for notching one edge of a sheet, devices for cutting strips of desired size from the sheet, a forming mandrel, mechanism for arranging the severed strips upon said mandrel, means for embossing the ends of the strip, devices for overlapping the embossed ends of the strips, and means for securing the lapped strip ends together to form annular metal bands.
11. In a machine for forming metal bands, the combination of means for notching one edge of a sheet, devices for cutting strips of desired size from the sheet, a forming mandrel, mechanism for arranging the severed strips upon said mandrel, means for embossing the ends of the strip, and means for welding the embossed ends together to form annular metal bands.
12. In a machine for forming metal bands, the combination of notching means, a forming mandrel, mechanism for arranging strips upon said mandrel, embossing means providing the said notched end of each strip with embossed portions extending parallel with its notched edges and also providing the unnotched straight end of said strip with embossed portions extending parallel with its end edge, devices for overlapping the ends of the strips and bringing the embossed portions of the straight end of each strip into engagement with the embossed portions of its corresponding notched end, and means for welding the ends together at the points of contact of the embossed portions thereof to form annular metal bands.
13. In a machine for forming metal bands, the combination of notching means, a forming mandrel, mechanism for arranging strips upon said mandrel at the same time flanging the edges thereof, devices for overlapping the ends of each strip and bringing the ends of the flanged edges of its straight, unnotched end into the notches of its notched end, and means for welding the overlapped ends together to form annular metal bands.
14. A machine for forming metal bands, comprising the combination of devices for cutting band strips from sheet stock, including a shearing element movable transversely to the sheet, a forming mandrel, means for arranging the severed strips upon said mandrel with their ends overlapped, and means for welding the overlapped strip ends together to form annular metal bands.
15. A machine for forming metal bands, comprising the combination of a sheet holder, feeding rollers for successively moving sheets through the holder and into notching positions, means for notching one edge of a sheet while so held, and locating devices for holding each sheet in an initial notching position, and means for rendering said locating devices inoperative relative to the sheet when in subsequent notching positions.
16. A machine for forming metal bands, comprising the combination of a sheet holder, feeding rollers for successively moving sheets through the holder and into notching positions, means for notching one edge of a sheet while so held, locating devices for holding each sheet in an initial notching position, and means for rendering said locating devices inoperative relative to the sheet when in subsequent notching positions, and devices for cutting band strips of desired size from said sheets.
17. A machine for forming a can part, comprising in combination, a sheet shearing mechanism, means for feeding a sheet of tin plate to said sheet shearing mechanism, a mandrel about which a sheared portion of said sheet is adapted to be progressively wrapped, and a transfer mechanism for transferring individual sheet parts from said sheet shearing mechanism to said mandrel, and cooperating therewith welding means for uniting the ends of said sheared and wrapped sheet-portion.
18. A machine for forming a blank for a

cylindrical can part, comprising a sheet shearing mechanism, means for feeding a sheet of tin plate to said sheet shearing mechanism, and a device operating in advance of said sheet shearing mechanism for performing a blank shaping operation, and cooperating therewith welding means for uniting the ends of said sheared and wrapped sheet-portion.
